TELEVIEWSING FLOOR REST

Josephine P. Argento, Chicago, Ill.

Application May 20, 1952, Serial No. 19,802

Term of patent 7 years

(Cl. D15—11)

To all whom it may concern:

Be it known that I, Josephine P. Argento, a citizen of the United States, residing at Chicago, county of Cook, State of Illinois, have invented a new, original, and ornamental Design for a Televiwing Floor Rest, of which the following is a specification, reference being had to the accompanying drawings, forming a part hereof.

In the drawings,

Fig. 1 is a front perspective view of a televiwing floor rest, showing my new design.

Fig. 2 is a front view of the same, with the head rest portion folded down;

Fig. 3 is a side elevational view of the same with the head rest portion folded down; and

Fig. 4 is a side elevational view of the televiwing floor rest in a changed position where it is used as a seat instead of in the reclining position shown in Figs. 1 and 3.

I claim:

The ornamental design for a televiwing floor rest, as shown.

JOSEPHINE P. ARGENTO.
